UNITED STATES PATENT OFFICE.

WINFIELD S. RUSSELL, OF NEW YORK, N. Y.

CALENDAR-HOLDER.

SPECIFICATION forming part of Letters Patent No. 658,511, dated September 25, 1900.

Application filed July 6, 1900. Serial No. 22,669. (No model.)

To all whom it may concern:

Be it known that I, WINFIELD S. RUSSELL, a citizen of the United States, residing at New York, in the county of New York and State 5 of New York, have invented certain new and useful Improvements in Calendar-Holders, of which the following is a full and complete specification, such as will enable those skilled in the art to which it appertains to make and 10 use the same.

This invention relates to combination calendar and memoranda holders; and the object thereof is to provide an improved device of this class whereby the several sheets of the 15 calendar may be securely held together and the separate sheets of which may be held in position wherein they may be readily viewed as thrown back successively day by day.

The invention consists in the construction 20 and arrangement of parts hereinafter described.

In the accompanying drawings, forming part of this specification, in which like reference characters denote like parts in the several views, Figure 1 is a perspective view of 25 a calendar-holder constructed according to my invention and a calendar connected therewith; Fig. 2, a section thereof upon the line 22 of Fig. 1, and Fig. 3 is a perspective view 30 of the main portion of the calendar-holder with the calendar detached therefrom.

In the practice of my invention I provide a calendar and memoranda holder, the main member of which is denoted by the general 35 reference character A, and which consists, preferably, of a single length of wire, the central portion of which is formed into a transverse base portion g, the wire at the ends thereof being bent upwardly to form upright 40 parallel portions f, which portions f terminate at their upper ends in looped portions e, which are merged into parallel downwardly-directed portions d, which portions d terminate in angular portions c, from which extend 45 the ends a and b of the said wire. The ends a and b are directed angularly relative to the portions d of the wire A in such manner that when the sheets B of the calendar, as herein-after described, are turned backwardly upon 50 the said portions d of the wire they will be unable to slip off from the end portions a and

b of said wire A, which might be the case if said end portions a and b were finally directed toward the transverse base portion g of the holder.

As shown in Figs. 1 and 2, the sheets B of the calendar are provided with spaced transverse perforations C, through which are passed the vertical portions f of the calendar-holder member A, whereby the lowermost 60 sheets B rest upon the transverse base portion g of the calendar-holder member. After all the sheets B have been passed upon the member A the ends a and b thereof are bent into the positions shown in the drawings, preventing detachment of the sheets B. The calendar-holder member A is provided with a supplemental member, denoted by the general reference character D, and which is preferably of integral construction, embodying 65 three angularly-directed members E, F, and G, the members E and G forming supports, whereby the member F ranges obliquely upwardly in the same plane as the member G, which is provided at its lower end with transverse perforations H, through which are 70 passed the portions d of the calendar-holder member A, as clearly shown in Figs. 1 and 2. In forming the supplemental member D the member F thereof is preferably cut or stamped 75 from the member E thereof, which member is then bent downwardly into its position angularly relative to the members F and G.

As it is desired to expose individually the sheets B of the calendar in position wherein 85 they may be readily observed, the respective sheet B is grasped and turned backwardly into the position shown in Fig. 2, in which it rests against the members G and F of the supplemental calendar member D. Two of 90 the sheets B are shown thus turned backwardly and supported in an upright position in Fig. 2, and it is manifest that in such position the sheets, or the uppermost one thereof, may be readily viewed above the other 95 sheets B, which are supported by the main member A.

The main member A is simple and cheap in construction and is admirably adapted for the purpose in view, firmly retaining the 100 sheets B of the holder in collected position. The supplemental member D supports the

2
sheets as they are turned back in proper position to allow an observer to readily view the date and memoranda thereon.

Having fully described my invention, I
5 claim as new and desire to secure by Letters
Patent—

1. A holder embodying a single length of
wire comprising the transversely-ranging portion
10 *g*, from either end of which range up-
wardly at substantial right angles the por-
tions *f*, adapted to receive calendar-sheets
thereon, which sheets in practice normally
rest upon the portion *g*, said portions *f* being
15 rearwardly turned to form curved por-
tions *e* which are bent downwardly to form
portions *d* ranging parallel with the portions
f and bent to form portions *a* and *b*, ranging
at angles thereto, to prevent the calendar-
20 sheets from detachment from the holder, to
form an auxiliary base to receive said sheets
thereon when the same are turned over the
curved portions, and to prevent said sheets
from turning under the holder, when the
25 same is raised or held in the hand, substan-
tially as shown and described.

2. A calendar-holder, comprising a main
member with which the several sheets of the

calendar are adapted to be loosely connected,
the said member embodying a pair of forward
rods adapted to receive the unturned sheets, 30
and a pair of rear rods adapted to receive the
turned-over sheets, and a supplemental mem-
ber operatively mounted upon the rear rods
and comprising a plate *D*, having a portion
35 *F* partially cut out therefrom and adapted to
be held at an upwardly-ranging diagonal an-
gle extending outwardly from the rear rods
to receive the calendar-sheets thereon when
the same are turned over, and the remainder
40 of the cut-out portion of the plate being adapt-
ed to be bent down at angles to the main body
of the plate at or near the center thereof to
support the portion *F*, and the whole plate *D*
being adapted to be folded over against the
45 calendar-sheets upon the forward rods, sub-
stantially as shown and described.

In testimony that I claim the foregoing as
my invention I have signed my name, in pres-
ence of the subscribing witnesses, this 29th
day of June, 1900.

WINFIELD S. RUSSELL.
